UNITED STATES PATENT OFFICE.

LEO D. JACOBY, OF BOSTON, MASSACHUSETTS, ASSIGNOR TO SANISPOON COMPANY, OF BOSTON, MASSACHUSETTS, A CORPORATION OF MASSACHUSETTS.

DESIGN FOR A TONGUE-DEPRESSOR.

52,766.

Specification for Design.

Patented Dec. 17, 1918.

Application filed August 21, 1918. Serial No. 250,889. Term of patent 14 years.

To all whom it may concern:

Be it known that I, LEO D. JACOBY, a citizen of the United States, residing at Boston, in the county of Suffolk and State of Massachusetts, have invented a new and original and ornamental Design for Tongue-Depressors, of which the following is a specification, reference being had to the accompanying drawings, forming a part thereof.

In the drawings Figure 1 is a plan view of a tongue depressor embodying my new design; Fig. 2 is a section on line 2—2 of Fig. 1; Fig. 3 is section on line 2—2 of Fig. 1.

What I claim is—

The ornamental design for a tongue depressor as shown.

LEO D. JACOBY.
